UNITED STATES PATENT OFFICE.

DAVID S. KENNEDY, OF BROOKLYN, NEW YORK, ASSIGNEE TO MERGENTHALER LINOTYPE COMPANY, A CORPORATION OF NEW YORK.

TYPOGRAPHICAL MACHINE.

1,115,210.

Specification of Letters Patent. Patented Oct. 27, 1914.

Application filed July 21, 1913. Serial No. 730,171.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had thereto to the accompanying drawing.

10 My invention relates to typographical machines, and more particularly to that class thereof equipped with a plurality of magazines.

15 It is often desirable to have at hand a considerable number of type or matrices representing additional characters, such as sorts or the like, and it is to this end that I employ a special arrangement of plural magazines, the escapements of which are controlled by independent keyboards, and wherein the type or matrices are delivered to a common belt, which in turn conveys them to the assembling point, and wherein a common distributing rail 20 rede- 25 livers them to their respective magazines. In these and other respects the general construction is somewhat similar to that of the linotype machine shown and described in the patent to Muehleisen, No. 608,067, 30 granted July 23, 1898. Although two magazines are herein specifically illustrated, it will of course be understood that the common assembling and distributing mechanism may be extended to co-operate with any 35 desired number of additional ones.

In the Muehleisen patent, the magazines are arranged side by side and an integral distributing bar or rail is provided, which extends entirely across the mouths of the 40 channels in both magazines. If such construction were closely followed in the present case, it might be necessary sometimes to change the entire distributor bar, and as it is my purpose to permit the employment of 45 a considerable variety of interchangeable magazines, it would in such circumstances be necessary to have a correspondingly large variety of distributor bars or rails, formed with different combinations and permutations. I therefore preferably employ a distributor bar or rail which consists of detachable sections, each section corresponding to one of the magazines in use, so that when another magazine is substituted for one of

them, the section of the distributor bar corresponding thereto may be removed and replaced by an appropriate section, without disturbing or affecting the section which operates with the magazine left in position.

In the use of such machines also, it is sometimes desirable to employ in the same magazine type or matrices of considerably greater or less thickness, as may be required for different classes of composition. To that end, I preferably employ a magazine, 65 rectangular in form, and provided with channels consisting of parallel grooves in the opposing plates, which engage the ears of the type or matrices in the customary manner. Because of this construction, I am 70 enabled to use either thin or thick type or matrices in one magazine, as occasion may demand. For instance, all the channels may be utilized to receive type or matrices of ordinary dimensions, or alternate channels 75 may be employed to receive thicker type or matrices, in which latter event the larger projecting body portions will extend over and into the intervening vacant spaces, it being understood that the grooves themselves are of sufficient size to accommodate 80 the ears of both classes. In addition I provide escapements and escapement actuating devices for all the channels, and also means for preventing the actuation of alternate 85 escapements, which means may be called into action at will, and are preferably in the form of a shield or plate adapted to cover the finger keys corresponding to the temporarily inactive escapements.

90 The accompanying drawings illustrate a linotype machine having my invention applied thereto, and except as hereinafter set forth, it may be of the general type illustrated in Letters Patent No. 436,532 to Mergenthaler, granted September 16, 1890, or in the Muehleisen patent previously mentioned. While I thus show a preferred embodiment 95 of my invention, it will be obvious that many changes and variations may be made therein, and in its mode of adaptation, which will still be comprised within its spirit. Thus, it may be similarly used in connection with typesetting and type-casting machines, or in fact any kind of typographical machines, which handles type, dies, or matrices. I therefore desire it to be 100 distinctly understood that I do not limit 105

myself to any specific form or embodiment, except in so far as such limitations are specified in the claims.

Referring to the drawings: Figure 1 is a perspective view of a linotype machine embodying my invention; Fig. 2 is a detached view, partly broken away, of the keyboard mechanism for the supplemental magazine; Fig. 3 is a detail view showing the sectional construction of the distributor rail or bar; Fig. 4 is a side view, partly in section, of the supplemental magazine, its keyboard mechanism, etc.; Fig. 5 is a side view of the shield for covering certain keys; Fig. 6 is a detached perspective of a construction detail; Fig. 7 is a transverse vertical section thereof; Fig. 8 is a view, similar to Fig. 2, of a modification; Fig. 9 is a side view thereof, partly in section; and Fig. 10 is a transverse section through the supplemental magazine.

Referring to the drawings, and generally speaking, the matrices X and X' are stored in the magazines A and C, and are released therefrom by the proper manipulation of the respective keyboards A' and D, whereby they are delivered upon the common assembling belt E, and by it in turn to the assembler B, from which the composed line is transferred to the casting mechanism. After the linotype is cast in the usual way, the matrices are conveyed to the top of the machine, and there delivered to the distributor bar or rail F—F', from which they drop into the magazines A and C, all in the manner well understood by those skilled in the art.

In the present instance I have shown one additional or supplemental magazine C, in line edgewise with the magazine A, to contain the extra matrices X' which may be desired from time to time in composition. The magazine C is rectangular in shape, as distinguished from the ordinary trapezoidal magazine A, and is formed in its opposite walls with two series of parallel grooves C^1 , of sufficient size to receive the ears of any matrices to be contained therein. This construction adapts the magazine to receive matrices of widely different thicknesses. For instance, Fig. 10 illustrates its capability to contain ordinary matrices X' in adjacent channels, or much thicker matrices X^2 in alternate channels, in which latter case the thicker body portions project into the intervening vacant spaces.

As shown in Fig. 4, the magazine C is carried by the base frame C', which is provided with the well known cam devices C'', whereby the frame may be moved to convenient position to permit the removal of the magazine and the substitution of another therefor. Mounted in the main frame, and in proximity to the end of the magazine C, when the latter is in operative posi-

tion, is a series of escapements M, one for each magazine channel, the escapements being held in normal position by springs M'. A vertical reed J is provided to operate each escapement, engaging it by its upper end, and resting at its lower end on one arm of the pivoted bell crank lever H, mounted in position to be rocked by the contacting push button or key G and G'. Each reed J is provided with a spring J', of sufficient strength to overcome the escapement spring M', and to hold the reed J, bell crank lever H, and push button G or G' in normal position, as indicated in Fig. 4. The reeds J are also notched to engage the transverse bar K, on which they normally rest.

It will be seen that the inward or longitudinal movement of a key or push button G or G' swings a bell crank lever H about its pivot, elevates a reed J, and permits the spring M' to move the corresponding escapement M to release the lowermost matrix; after which the spring J' restores the parts to their normal position. If for any reason, it is desired to remove the escapements M from the frame, it is necessary first to relieve them from their engagement with the reeds J and the tension of the spring J', and this is preferably effected by the upward movement of the transverse bar K, which is supported and guided in the machine frame by the screws K' and is formed with the depending projections K'', located in position to engage the cam surfaces L' on the rock shaft L, an external handle L' being connected to the latter to turn it and facilitate the adjustment of the parts.

As previously set forth, and as shown in Fig. 10, the magazine C is adapted to contain matrices X' of the ordinary dimensions, in which event all of the channels therein are utilized, or matrices X^2 of considerably greater thickness, in which event they are located in alternate channels. In the use of the magazine in the latter circumstances, it is desirable that the escapements corresponding to the alternate vacant channels be locked against actuation. The keyboard D (see Fig. 2) is shown as provided with four rows of keys, the upper two rows of keys G actuating the second, fourth, sixth, etc. of the reeds J, and the lower two rows of keys G' actuating the third, fifth, seventh, etc. of the reeds J. In the event that the thicker matrices X^2 are to be employed, and are disposed in the second, fourth, sixth, etc. channels of the magazine, I may prevent the actuation of the escapements corresponding to the third, fifth, seventh, etc., of the channels by the manually adjustable shield or plate N (see Fig. 5). The shield N is pivotally mounted on the frame and is provided with the external handle N', whereby it may be

removed to operative position, as indicated by full lines, or to inoperative position, as indicated by dotted lines. In the former, the lower keys G' are covered and the operator 5 is prevented from manipulating any of the keys except the upper ones G corresponding to the thicker matrices in use; while in the latter he is free to select among all the keys G and G' , so as to release matrices 10 from any of the magazine channels.

In Figs. 8 and 9, I have shown a modification, wherein I employ a movable plate O , provided with the handle O' and catch O'' , and similar to the previously-described 15 plate N , except that it is of greater extent and in operative position covers both sets of keys G and G' , and further is provided with a series of supplemental keys P adapted to engage and actuate the upper two rows of 20 keys G . This form is advantageous in that the keys P may be marked with designating characters different from those on the keys G , but corresponding to the special set of matrices then in the magazine, thus 25 avoiding a change of buttons on the keys G , or the confusion that might otherwise occur.

For purposes of illustration, the improvements have been described and shown in 30 connection with ordinary matrices located in successive channels, and thicker matrices located in alternate channels, but obviously the same principles may be applied in connection with even thicker matrices, which 35 would occupy three or any desired number of channels.

As previously stated, in the Muehleisen machine, the distributor bar or rail is extended entirely across the upper ends of both 40 magazines, so as to carry and deliver the matrices to their appropriate channels in either of them, and in the present instance the general principle remains the same, the matrices being passed along the rail portion 45 F , from which some drop into the magazine A , and then along the continued portion F' , from which the others drop into the magazine C . In order, however, to adapt the machine to a considerable variety of 50 interchangeable magazines, I prefer to construct the rail in two separable sections F and F' , which may be secured together in any desired manner, as by a bolt F'' . For instance, in Fig. 3, the rail section F is 55 shown as formed with sustaining lips or teeth of greater extent than that of the similar sustaining lips or teeth on the section F' , this difference being indicated by the dotted lines 1-1 in connection with the section F , and the dotted lines 2-2 in 60 connection with the section F' . Assuming by way of example, that for the magazine C another magazine should be substituted containing a different number of channels, or 65 that it be arranged to carry matrices of a

different size, it may be necessary that the section F' have different sustaining lips or teeth, or lips or teeth of different extent. My improved construction enables me to comply with this requirement without removing the entire distributor rail from the machine and substituting another therefor, it being merely necessary to replace the section F' by one corresponding in formation and permutation to the matrices which are 70 brought into play by the new magazine, or to the thicker or thinner substituted matrices. In other words, the sectional constriction of the distributor rail allows me to adapt the distributing mechanism to any 75 change of matrix or face with the minimum of expense and trouble. In many instances, no substitution will be necessary, as the ordinary permutation of the distributor teeth will release the matrices into the proper 80 channels, but where such change is required, it may readily be effected by the detachable construction described.

As previously stated, I have presented my improvements only in preferred form 85 and by way of example, and as applied to a linotype machine, but obviously many modifications and alterations therein, and in its mode of adaptation, will suggest themselves to those skilled in the art, without departure 90 from its scope.

Having thus described my invention, its construction and mode of operation, what I claim and desire to secure by Letters Patent 95 of the United States, is as follows:

1. In a typographical machine, the combination of a magazine formed with grooved channels for the type or matrices, a bank 100 of escapements therefor one for each channel, and means to permit the operation of all the escapements or prevent the operation of alternate escapements, to adapt the mechanism for the delivery of type or matrices from all of the channels, or of thicker type 105 or matrices from alternate channels, at will. 110

2. In a typographical machine, the combination of a plurality of escapement actuating devices divided into sets, those of one set being alternated with those of another set, finger keys for operating said devices, 115 and means for preventing the manipulation of the keys of one of said sets when desired.

3. In a typographical machine, the combination of a plurality of escapement actuating devices divided into sets, those of one set being alternated with those of another set, finger keys for operating said devices, and a movable shield to cover the keys of one of said sets. 120

4. In a typographical machine, the combination of a plurality of escapement actuating devices divided into sets, those of one set being alternated with those of another set, finger keys for operating said devices, 125 130

and means for permitting or preventing the conjoint operation of the finger keys of both sets, as required.

5. In a typographical machine, the combination of a bank of escapements divided into sets, those of one set being alternated with those of another set, and means for permitting or preventing the conjoint actuation of said sets, as required.

10 6. In a typographical machine, the combination of a plurality of escapements, a corresponding plurality of actuating devices therefor, said actuating devices being divided into sets, those of one set being alternated with those of another set, and means for permitting or preventing the conjoint actuation of said sets, as required.

15 7. In a typographical machine, the combination of a plurality of escapement actuating devices divided into sets, those of one set being alternated with those of another set, and means for permitting or preventing the conjoint actuation of said sets, as required.

20 8. In a typographical machine, the combination of a plurality of escapement actuating devices divided into sets, those of one set being alternated with those of another set, a corresponding plurality of coöperating finger keys similarly divided into sets, and means for preventing the manipulation of one of said sets of finger keys.

25 9. In a typographical machine, the combination of a plurality of escapement actuating devices divided into sets, those of one set being alternated with those of another set, finger keys for operating said devices,

and a movable plate to cover all of said finger keys, and provided with auxiliary keys for operating only those of one set.

40 10. In a typographical machine, the combination of a series of escapements arranged side by side, and individual finger keys for operating the escapements and divided into sets, the keys of the respective sets being arranged to operate alternate escapements in the series, and means for preventing the operation of one set of keys when desired.

45 11. In a typographical machine, the combination of a magazine adapted to contain different fonts of type or matrices, one font having fewer characters than another, a bank of escapements to control the delivery of the type or matrices from the magazine, and means for permitting the operation of all of the escapements or preventing the operation of certain of them to adapt them to one or another of the fonts.

50 12. In a typographical machine, the combination of a plurality of escapement actuating devices divided into sets, one set alone adapted to be used in the delivery of type or matrices of one font, and all of said sets adapted to be used conjointly in the delivery of type or matrices of another font, and means for permitting or preventing the conjoint operation of said sets as required.

In testimony whereof I have affixed my signature in presence of two witnesses.

DAVID S. KENNEDY.
